F. RAUCH.
COMBINED PEN AND CIGAR LIGHTER.
APPLICATION FILED JULY 23, 1920.
1,379,213. Patented May 24, 1921.

Frank Rauch
By his Attorney
Charles L. Wright

UNITED STATES PATENT OFFICE.

FRANK RAUCH, OF BROOKLYN, NEW YORK.

COMBINED PEN AND CIGAR-LIGHTER.

1,379,213.

Specification of Letters Patent. Patented May 24, 1921.

Application filed July 23, 1920. Serial No. 398,435.

To all whom it may concern:

Be it known that I, FRANK RAUCH, a citizen of Jugo-Slavia, (and a declarant for United States citizenship), residing in Brooklyn, in the county of Kings and State of New York, have invented certain new and useful Improvements in Combined Pen and Cigar-Lighters, of which the following is a specification.

10 The main purpose of this invention is to provide a device for producing a flame, such as may be used to light a cigar, cigarette or the like, or as a torch, the device being combined with the cap of a fountain pen of the ordinary type.

Another purpose is to provide such devices in forms which are convenient to use, compact in structure, inexpensive to manufacture, and neat in appearance, being really 20 indistinguishable from the usual cap for which they may be substituted.

These and other objects, which will become more fully apparent as the description progresses, are attained by the novel construction, combination and arrangement of elements hereinafter fully described and shown in the accompanying drawings, forming an essential part of this disclosure, and in which:—

30 Figure 1 is a side elevational view of the lighter as combined with a conventional type of fountain pen.

Fig. 2 is a plan view of the cap with the tip removed, drawn to an enlarged scale.

35 Fig. 3 is a longitudinal sectional view taken through the cap with its tip in position.

Fig. 4 is a longitudinal sectional view of the device showing its interior construction.

40 Fig. 5 is a similar view of the same taken in a plane at a right angle to that of Fig. 4.

Fig. 6 is a transverse sectional view of the device taken on line 6—6 of Fig. 4.

Fig. 7 is a perspective view of the abrader 45 and its mounting in detail.

Fig. 8 is a longitudinal sectional view, similar to Fig. 4 but showing a modified form of the device.

Referring to the drawings in detail, the 50 numeral 10 designates the body of a commercial type of plain or self-filling fountain pen, the exterior of which is screw-threaded slightly tapered or made conical in order to receive the usual cap and cause it to normally adhere with sufficient tension to re-

main in position, either acting as a guard or casing for the pen nib or point, or, if the pen is in use, as a prolongation of the body.

In the present invention a special cap 15 is provided, it being substantially of the same outside dimensions and containing a slightly conical bore 16 fitting the ends of the pen body and receptive of the pen point when in engagement.

The opposite, outer end of the cap contains a straight cylindrical bore 17 extending to an interior shoulder or abutment 18 and is open to the inner, smaller end of the bore 16.

Fitted snugly to the bore 17 is a cylinder 20, its open inner end resting against the shoulder 18, its outer end protruding somewhat beyond the corresponding end of the cap. Within the cylinder is a removable tank 21 having a closed lower end 22 and a similar closed upper end 23, except for openings further described, the plate 23 covering the upper end extending marginally outward to cover the end of the cylinder 20.

A small tube 24 is secured to the inner end 80 end plate 22 near one side of the chamber, the tube extending through the head 23, above which it is curved toward the center and finished with a beveled end 24', in which is inserted a wick 25, passing out at the 85 open recess 26 formed in the wall of the tube, and into the interior of the tank so as to be saturated with combustible liquid entered through its open upper end.

Fixed to the opposite wall of the tube, 90 and to the plate 22 is the curved wall of a flattened casing 28, its side elements being soldered their entire length, liquid tight, to the walls of the tank 21, the walls of the casing being adapted to resiliently grasp 95 and tightly engage a stick 30 of pyrophoric material entered through an opening 31 in the inner end 22 of the tank.

A bent flat spring 32 is fastened to the interior of the casing immediately above the 100 inner end 22, its upper bowed portion 33 being normally in contact with the pyrophoric material, while its extreme end is curved outwardly and is free to move below the plate 23, in which is formed an open 105 elongated slot 34.

The tip or cover 35 for the cap is formed with an integral top 36 and has a bored opening 37 containing a sleeve or bushing 38, adapted to neatly fit the extending end 110

of the cylinder 20, a counterbored beading 39 formed at the end of the tip, being engageable over the extreme top of the cap 20.

- Fixed rigidly at the bottom of the bore 5 37 to the inner surface of the sleeve 38, is a semi-circular plate 40, from which extends, centrally of the top tip and toward its open end a spring element 41, bent outward, opposite to the plate 40 and forming 10 a stop 42 adapted to make contact with the interior of the sleeve at a point sufficiently remote from its end as to avoid interference with the cylinder 20 when the tip is positioned on the cap.
- 15 Secured centrally to the spring element 41 is the shank of an abrader bar 44, the same being in its extending operative length equal to the length of the chamber 20, and provided with teeth or serrations 45, preferably of ratchet shape and adapted to act in the manner of a file when in contact with the pyrophoric material, the abrader entering the chamber through the slot 34, its point extending through an opening in the 25 inner end wall of the chamber.

In the modification shown in Fig. 8 the same general structure is preserved, except the spring 32 is replaced by another flat spring 50 tensioned to spring outwardly or 30 away from the stick 30 but which may be forced against the abrader 44, when it is withdrawn, by pressing the knob 51, extending through the wall of the cap.

This knob is provided with a stem 52 35 in contact with the spring and is prevented from movement outward by a flange 53, thus enabling an operator to exert any desired pressure of the abrader against the pyrophoric material.

40 As the knob passes through the wall of the cylinder and then into the wall of the casing direct, no opening exists for leakage of the liquid contained in the tank.

In operation, the wick is entered into the 45 tube 24 and extended outward for a short distance, its inner end being free within the tank 21, which may be lightly packed with absorbent material, as cotton, and filled with a combustible liquid, as alcohol, gasolene 50 or the like.

The stick of pyrophoric material 30 is passed into its casing through the opening 31 and pressed toward the tube by the spring 32.

55 The tip and its attached parts are applied to the extending part of the chamber, and as the tip and cap are identical in diameter and appearance, the joint is hardly perceptible, while the combined length is 60 not noticeable.

When a light is desired, the tip is pulled 65 briskly outward, off the cap, this movement causing the serrations of the abrader, held tightly against the pyrophoric material, to cause the same to emit a shower of

sparks, which, due to their direction and closeness to the projecting end of the wick 25, maintained in a moistened condition by capillary attraction, causes the same to ignite and produce a flame in a well known 70 manner.

As the walls of the cylinder extend outward beyond the end of the cap, usually made of hard rubber, it is not injured by the heat, while the tip is removed entirely. 75

The flame may be quenched in any convenient manner, or by replacing the tip in position, it being noted that sparks are not caused by the insertion of the abrader, but only upon its rapid retraction, due to the 80 shape of the teeth.

It will also be evident that full and economical use of the pyrophoric material is obtained, as the abrader is not rigidly but yieldingly mounted, and spring pressed 85 against the entire length of material during its movement.

Having thus described my invention, and set forth the manner of its construction, and use, what I claim as new and desire to secure by Letters Patent, is:—

1. A lighter comprising an inner and outer casing, pyrophoric material and a flat spring disposed longitudinally in said inner casing, a tip engageable with said outer 95 casing, and a yieldingly mounted abrader carried by said tip adapted to operate under the tension of said spring upon said pyrophoric material, when the tip is being withdrawn.

2. A lighter comprising an inner and outer casing, pyrophoric material and a flat spring secured lengthwise in said inner casing, a cover tip engageable with said outer casing, a spring in said tip, a bar 105 mounted on the spring, and ratchet teeth on said bar adapted to be pressed into engagement with said pyrophoric material by said flat spring whereby sparks are produced on retraction of said bar and avoided 110 upon its insertion.

3. A lighter comprising a cylindrical outer casing partially embedded in the end of a pen cap, a cover forming a prolongation of said cap engageable on the protruding end of said casing, a flattened casing within the first named casing, a stick of pyrophoric material in said inner casing, a serrated bar yieldingly mounted in said cover and adapted to enter the inner casing, and a bent flat spring fixed in the inner casing adapted to press the teeth of said bar into abrading contact with said stick. 115

4. A lighter comprising a cylindrical outer casing partially embedded in the end 120 of a pen cap, a cover forming a prolongation of said cap engageable on the protruding end of said casing, a flattened casing extending the entire length within the first named casing, a stick of pyrophoric ma- 125

- terial in said inner casing, a serrated bar yieldingly mounted in said cover and adapted to enter the inner casing, means for exerting pressure on said bar against said stick, 5 and a tube open to said outer casing and bent to register with the end of said stick, said tube containing a wick communicating with liquid in the space between said casings.
- 10 5. A cigar lighter comprising a pen cap, a container for liquids set in one end of said cap, and extending therebeyond, a casing in said container containing pyrophoric material, a wick tube in said container, its outer end being contiguous to said material, a cover engageable on said container, a yielding abrader carried by said cover, said abrader having ratchet shaped teeth, and means for pressing the teeth of said abrader
- 15 in contact with the pyrophoric material 20 during its retraction, whereby sparks are caused to ignite a wick in said tube.
6. A cigar lighter comprising a pen cap, a container for liquids set in one end of said cap and extending therebeyond, a casing in said container containing pyrophoric material, a wick tube in said container, its outer end being contiguous to said material, a tip, a bushing in said tip fitted to engage the extending end of said container, a spring 30 fixed in said bushing, an abrader carried by said spring, means in said casing for pressing said abrader against said pyrophoric material and a guide in said container for the abrader. 35

In testimony whereof I have signed my name to this application.

FRANK RAUCH.
